UNITED STATES PATENT OFFICE.

KARL KEYSSNER, OF NUREMBERG, GERMANY.

CUTTING-MACHINE FOR MAKING BALL-BEARINGS.

SPECIFICATION forming part of Letters Patent No. 643,381, dated February 13, 1900.

Application filed June 26, 1897. Serial No. 642,507. (No model.)

To all whom it may concern:

Be it known that I, KARL KEYSSNER, a subject of the German Emperor, residing at Nuremberg, Kingdom of Bavaria, Germany, have invented certain new and useful Improvements in Cutting-Machines for the Making of Bearing-Balls, of which the following is a specification.

The present invention relates to improvements in ball-cutting machines, tending to a complete rounding off of the balls as their entire surface is equally exposed to the peculiar action of the cutting-rings.

The improvements comprise also advantageous arrangements in the construction of the machine by which space, material, and work are saved.

The annexed sketches illustrate the invention.

20 Figure 1 is a vertical middle section of the machine; Fig. 2, a horizontal section above the table; Fig. 3, a view of a grinding stand-axle, and Fig. 4 a view of a cutting-plate from above.

25 The construction of the machine is such that on a table with the pillars *a* and the board *b* there are several cutting-stands, which are in common driven by the central gearing-axle *c*. The gearing-shaft *d*, with

30 the pulleys *e*, is mounted, like the vertical axle *c*, on the traverse-beam *f* and between the pillars *a*. The bevel-gear *g* on the gearing-shaft *d* moves two conical gear-wheels *h* and *i* in opposite directions. The former is mounted fast on the axle *c*, while the latter is loose and bears on its prolonged nave a spur-wheel *k*. The latter drives the wheels *m* on the stand-axles *l*, which move the upper cutting-plates *n*. The nether cutting-

40 plates *o* are mounted on sleeves *p*, which are mounted on the axles *l*. The plates *o* are driven by the wheels *q*, which are set in motion by the spur-wheel *r* on the axle *c*. Each stand has its bearing in an eccentrically-bored bush *s*, which can be turned by means of handles *t* in the eye *u*, so that the wheels *m* and *q* can be disengaged from the wheels *k* and *r* and each stand shut out. To prevent the cutting-plates, which run in oppo-

45 site directions, from turning the balls around one axle only, which makes the balls oval, the axle *l* has been bent at right angles—

that is, the upper part *l'* is eccentric to the lower part *l*—so that the plates *n* and *o* will also work eccentrically. By the eccentric 55 movement the balls between the rings *v* are turned in different directions, and so the whole surface of the balls is equally worked upon, which will make them evenly round. The eccentric motion of the rings *v* does not 60 permit the balls to be run in shaped ring grooves, wherefore a new kind of rings *v* is used with a rough file-like surface. The rings are so cut and arranged that the edges of the file strokes run against one another, and 65 consequently work upon one another. The balls are worked in the manner of files by the plates *n* and *o* having a little different rate of velocity. The pieces of steel which are to be made into balls are cut off from 70 round bars and are made to run first between coarse rings, then between fine, and afterward between smooth ones, whereupon they are mathematically round and smooth. The necessary pressure between the rings *v* is produced by the tension of spiral springs *w*. 75

Having thus described my invention, what I claim is—

1. A ball-grinding machine consisting of a series of cutting-stands mounted eccentrically to their drive-shaft, cutting-plates having annular cutting-faces, mechanism for rotating said stands, and means for throwing said mechanism in and out of gear with said stands, substantially as set forth. 80

2. In a ball-grinding machine, the combination of a main driving-shaft, a vertical shaft carrying a series of spur-wheels some of which are loosely, and others tightly mounted on said shaft, a plurality of cutting-stands composed of eccentric axles mounted in eccentric bushings and carrying spur-wheels adapted to mesh with the spur-wheels on the vertical shaft, cutting-wheels mounted on said stands and having annular cutting-faces, means for throwing said spur-wheels in and out of gear, substantially as described. 85 90 95

In testimony whereof I affix my signature in presence of two witnesses.

KARL KEYSSNER.
